(57) **CLAIM**

The ornamental design for a headlight module for work vehicle, as shown and described.

DESCRIPTION

FIG. 1 is an elevated perspective view of the right side headlight module for a work vehicle as seen from the right front of the work vehicle embodying our new design, with the broken line showing for illustrative purposes only and forming no part of the claimed design;

FIG. 2 is a front elevation view of the right side headlight module;

FIG. 3 is a right-side elevation view of the right side headlight module;

FIG. 4 is a back elevation view of the right side headlight module; and,

FIG. 5 is a top plan view of the right side headlight module. This design contemplates a symmetric headlight module embodiment on the left side, which is a left mirror image of the right side headlight module.
